UNITED STATES PATENT OFFICE.

SAMUEL M. HOLTON, OF BATTLE CREEK, MICHIGAN.

LABEL AND TICKET RECEPACLE.

SPECIFICATION forming part of Letters Patent No. 269,418, dated December 19, 1882.

Application filed May 20, 1882. (Model.)

To all whom it may concern:

Be it known that I, SAMUEL M. HOLTON, of Battle Creek, Calhoun county, Michigan, have invented a new and Improved Label and Ticket Receptacle, of which the following is a full, clear, and exact description.

The object of my invention is to provide a new and improved receptacle for labels, tags, or tickets, in which receptacle the labels, &c., cannot get mixed, and from which they can be removed very easily.

Reference is to be had to the accompanying drawings, forming part of this specification, in which similar letters of reference indicate corresponding parts in both figures.

Figure 1 is a perspective view of my improved receptacle for labels and tickets, and Fig. 2 is a longitudinal sectional elevation of the same.

A drawer or shallow box, A, is divided into a series of compartments, B, according to the sizes of the tickets, labels, cards, tags, &c., to be placed therein, by a series of longitudinal and transverse strips, C and D, placed edge-wise and crossing each other at right angles, which strips or partitions C and D are preferably about one-half an inch thick. Rods or wires E are passed through the longitudinal partitions C near the upper edges, so that the rods or wires E will cross the compartments transversely at or near the middle. The transverse partitions D are provided between each

two longitudinal partitions C with a recess, F, extending almost to the bottoms of the partitions, and of sufficient size to admit a finger. 35 The labels G, tags, &c., are placed in the compartments B and under the rods or wires E, which hold the labels in their compartments and prevent mixing of the labels, &c. The finger can be conveniently passed into the recesses F in the transverse partitions D for withdrawing or removing the labels. A number of these drawers or boxes can be combined in one case or box. These drawers will be found to be of the greatest convenience, as the 45 mixing of the labels, which is the cause of so much annoyance and of mistakes, is avoided and the labels can be removed easily.

Having thus described my invention, I claim as new and desire to secure by Letters Patent— 50

In a label and ticket receptacle, the combination, with the box or drawer A, of the longitudinal and transverse partitions C D, the latter provided with recesses F at the ends of the compartments formed in the partitions, and of 55 the wires E, extending transversely across the compartments at or near the middle of the same, substantially as herein shown and described, and for the purpose set forth.

SAMUEL M. HOLTON.
